VALVE RETAINER FOR GLASS TUBING

Roy Forrest Davis, Jr., 818 E. 22nd St. Court,
Des Moines, Iowa

Filed May 3, 1962, Ser. No. 69,963

Term of patent 14 years

(Cl. D16—1)

FIG. 1 is a perspective view of a valve retainer for glass tubing embodying my new design,

FIG. 2 is a perspective view taken from the opposite side of FIG. 1,

FIGS. 3 and 4 are respective elevational views from the opposite sides thereof,

FIG. 5 is an end view thereof, and

FIG. 6 is a cross sectional view taken on the line 6—6 of FIG. 1 with portions of two glass tubing sections joined by a coupling and a valve assembly shown in broken lines for illustration purposes only.

I claim:

The ornamental design for a valve retainer for glass tubing, as shown and described.
